CHARLES PFEIFFER AND FRANK A. WASSON, OF MILWAUKEE, WISCONSIN.

OIL-WELL WASHER.

1,375,106.

Specification of Letters Patent. Patented Apr. 19, 1921.

Application filed July 6, 1920. Serial No. 394,254.

To all whom it may concern:

Be it known that we, CHARLES PFEIFFER and FRANK A. WASSON, citizens of the United States, and residents of Milwaukee, 5 county of Milwaukee, and State of Wisconsin, have invented new and useful Improvements in Oil-Well Washers, of which the following is a description, reference being had to the accompanying drawings, which 10 are a part of this specification.

The invention relates to an oil well washing apparatus.

In many oil wells the flow of oil is prematurely stopped due to the clogging of the 15 wall cavity by congealed paraffin, loose sand, asphalt and other detrital substances in the oil bearing sands surrounding the cavity. If this material can be dissolved and washed away the well may again be put on a production basis. It is the object of this 20 invention to provide an efficient well washing apparatus for washing the walls of the cavity to free the oil bearing sands surrounding the same, of congealed material, 25 sand and other detrital substances which prevent the flow of oil.

The invention further consists in the several features hereinafter set forth and more particularly defined by claims at the conclusion hereof.

In the drawings: Figure 1 is a vertical sectional view of an apparatus embodying the invention; Fig. 2 is an enlarged detail sectional view of the apparatus; Fig. 3 is a 35 section taken on the line 3—3 of Fig. 1.

In the drawings, the numeral 4 designates the well cavity and 5 the casing leading from above ground to the cavity. Strata 6 of oil bearing sands and other strata 7 of 40 shale, slate or rock surround the cavity 4.

When the oil bearing sands adjacent the cavity become clogged with sand, paraffin, asphalt, etc., the flow of oil to the cavity is stopped and to reestablish this flow we 45 provide a pump 8 at the lower end of a tube 9, and a casing 10 surrounding the tube 9 and connected to the main casing 5.

The pump 8 is a suction pump and is operated from above ground by the pump 50 rod 11, the inlet end 12 of the pump being disposed near the bottom 13 of the cavity.

The casing 10 telescopes within the main casing 5 and projects into the cavity. A 55 flushing nozzle 14 is formed on the lower end of this casing by means of the conical portion 15 having a flaring end and a conical

deflector 16 mounted on a guide tube 17 which is slidably mounted on the pipe or tube 9. The size of the nozzle opening may be varied by spacing the deflector 16 at different distances from the end 15. This adjustment is accomplished by connectors 18 carried by the tube 17 and having an adjustable connection with the casing 10 by means of clamping bolts 19 and slots 20. The casing 10 is moved up or down on the pump tube so as to raise or lower the nozzle by means of cables 21 secured to the upper end of said casing and passing up through the casing 5 to a point 70 above ground.

The operation of washing the well with the above apparatus is as follows: The wash water, preferably hot water, is dropped through the conduit formed between the casings 5 and 10 and the tube 9 and issues from the nozzle 14 under considerable pressure due to the head acquired by its fall, and is sprayed against the wall of the cavity, penetrating the sands and dissolving and 80 washing out the congealed paraffin, asphalt and loose sand around the cavity. The water and loose material drains to the bottom of the cavity where it is sucked up by the pump 8 and delivered through the tube 9 which conducts it out of the well. The wash water may be sent down into the cavity by using a force pump but pressure created by its own drop from the ground level to the cavity is sufficient and simpler, and is therefore 85 preferred. The preferred method of operation is to remove the wash water from the bottom of the well as fast as it collects therein with the result that the water pressure is not permitted to increase the pressure 90 existing in the cavity, and the forcing of the oil back into the sand is therefore prevented. By this process of washing the full effect of the water spray against the walls of the cavity is obtained and the nozzle is 95 not immersed at any time in the wash water. By raising or lowering the casing 10 the nozzle is moved to different elevations in the well cavity so as to spray the entire cavity.

Thus, in washing a well, the pump is put 100 into operation and the casing with the nozzle at the upper or top of the cavity is gradually fed downwardly while the spray washes the walls.

Where the volume of loose sand and other 110 solid material to be raised from the cavity is unusually large air or other suitable fluid

under pressure may be applied to the solution above the pump to assist in forcing the sand and other solids out of the well. For this purpose compressed air is conducted through a pipe 22 down to the lower end of the tube 9 and above the pump.

We desire it to be understood that this invention is not limited to any specific form or arrangement of parts except in so far as 10 such limitations are specified in the claims.

What we claim as our invention is:

1. In a well washing apparatus, the combination of a flushing nozzle movable to different heights within the well cavity, 15 means for conducting wash liquid to said nozzle from a point above ground, a suction pipe extending into the cavity and forming a guide for said nozzle, and a suction pump connected with said pipe for removing the 20 wash liquid from the cavity.

2. In a well washing apparatus, the combination with a conduit, of a conduit having telescoping engagement with said first named conduit and provided with a flushing nozzle, means for raising and lowering the conduit carrying the nozzle to vary the position of the nozzle in the well cavity, and a pump for removing the washing liquid from 25 the cavity.

3. In a well washing apparatus, the combination of a conduit for conducting wash liquid into the well cavity, a flushing nozzle on the lower end of said conduit, a suction pipe extending into the cavity and disposed 30 within said conduit, and a suction pump con-

nected with said pipe and disposed in the well cavity.

4. In a well washing apparatus, the combination, with the well casing, of a conduit having telescoping engagement with said 40 casing and provided with a flushing nozzle, means for raising and lowering the conduit to vary the position of the nozzle in the well cavity, a suction pump adjacent the bottom of the well cavity, and a delivery pipe from 45 the pump extending through said conduit and casing to a point above ground.

5. In a well washing apparatus, the combination of a conduit having a contracted end, a guide tube centrally supported in said 50 end, a deflector mounted on said tube and co-operating with the end of said conduit to form an annular flushing nozzle, a suction pipe extending from a position above ground into the well cavity and upon which 55 said guide tube is mounted, and a pump in the well cavity connected to said pipe.

6. In a well washing apparatus, the combination of a conduit for conducting the washing liquid into the well cavity, a flushing nozzle in the cavity connected to the lower end of said conduit, a pump within the cavity, a delivery pipe connected to the pump, and means for introducing fluid under pressure into the delivery pipe above 60 the pump.

In testimony whereof, we affix our signatures.

CHARLES PFEIFFER.
FRANK A. WASSON.
